UNITED STATES PATENT OFFICE.

HANSON TAMS, OF STAUNTON, VIRGINIA.

WINDOW SCREEN.

Application filed November 13, 1923 Serial No. 674,519.

This invention relates to window screens, the improvements in general applying to screens of the adjustable, or non-adjustable types.

5 An important feature of the invention comprises a screen which is adapted to fit between the guide strips on the opposite sides of the window frame outside of the lower sash, such screen being mounted to swing or tilt inwardly, and being removable while in such tilted position. An advantage of this construction and arrangement is that the screen may be located outside of and may fit against the outer face of the 10 lower portion of the sash, thus permitting the sash to be raised or lowered without removing the screen.

15 Another important feature of the invention is comprised in a screen of the character referred to having facility for easy removal from or insertion into position in the window frame, and without the use of the usual guide strips, which frequently swell from dampness, rendering the movement of the 20 screen up or down difficult.

25 Another important feature of the invention is a screen of the adjustable type in which means are provided for reliably guiding the members as they slide on each other to vary the width of the screen, and an improved means for limiting the extent of the outward movement of the sliding members, and at the same time permitting a maximum extension of the screen members 30 as compared with known constructions.

35 Other important features of the invention, including details of construction and arrangements of parts, will be better understood from the following description, in connection with the accompanying drawings, in which:

40 Fig. 1 is a front view of a portion of a window frame with a screen embodying the present invention in position therein;

45 Fig. 2 is a sectional view through the frame of the window, showing, in elevation, one end of the screen;

50 Fig. 3 is a similar view illustrating the screen in tilted position prior to removal;

55 Fig. 4 is a sectional detail view, enlarged, illustrating the two plates which are set

into the screen edge, and the pins cooperating therewith;

Fig. 5 is an edge view illustrating the same parts;

55 Figs. 6, 7, and 8 are detail views of the adjacent ends of the sliding screen members;

Fig. 9 is a section on the line 9—9 Fig. 6, in the direction indicated by the arrow 9;

60 Fig. 10 is a section on the same line in the direction indicated by the arrow 10;

Fig. 11 illustrates a solid or non-adjustable screen in elevation, and

Fig. 12 shows, in side elevation, the edge 65 of the same screen.

The adjustable screen illustrated in elevation in Fig. 1 comprises the two slidable members 1, 2, whose upper and lower pairs of rails 19, 21, have dove-tail tenons 3 sliding in grooves 4. These dove-tail guides 70 extend substantially the entire length of the screen sections, and thus said sections are truly guided with reference to each other and the danger of sticking or imperfect 75 slidable action is avoided. The tenon 3 is cut off or discontinued near the end of the rail 19, and in the space between the end of the tenon and the adjacent end of the rail 19 is located a pawl 14, pivotally mounted on a screw or pin 14^a, the screw being 80 located close to the end of the rail. The cooperating rails 21 are provided at their ends with shoulders 22, formed by making notches 22^a in the lower sides of the grooves 4, as shown in Fig. 8. When the screen 85 members are extended the distance of such extension is limited by the engagement of the shoulders 22 with the pawls 14, as indicated in Fig. 6. The construction described affords a reliable means for stopping the 90 movements of the screen sections, and by reason of the fact that the shoulders 22 are located at the outer extremities of the sections a greater amount of extension 95 of the screen is permitted than would be possible with the commercial form of adjustable screen in which the sections carry blocks, engagement of which with each other limits the extension of the screen at such a point 100 that there is a considerable amount of overlapping of the screen sections, which is objectionable.

The upper rail 19 of the screen section is provided with an angular inwardly extending strip 15, which overlaps the rail 21, the inner face of this strip lying flush with the 5 vertical inner face of the rail 21 as shown in Figs. 9 and 10. The strip 15 closes the space between the adjacent face of the sash rail S and the rail 19, and prevents the entrance of flies at this point. The use 10 of the strip 15 is necessary in view of the fact that this screen is located between the sash guiding strips, or blind stops 13, 13, instead of being inserted inside of these strips, as is usual.

15 The outer edges of the side rails of the screen sections 1, 2 are provided with recesses 23 covered by plates 5 each of which has a slot 6 provided with a lateral opening 7, and headed pins or screws 8 are inserted at opposite points in the blind stops 20 13 for cooperation with said plates. The screws 8 are so located that they will occupy positions intermediate the ends of the slots 6 when the screen is in proper position. To 25 insert the screen the openings 7 are placed opposite the screws 8, and the latter are caused to pass into the openings with the heads of the screws inside the plates, and received in the recesses 23, while the screen 30 is in an inclined position as shown in Fig. 3. The screen is then swung into a vertical position.

At suitable points below the plates 6 the 35 screen members are provided with recesses 24 covered by plates 12 having open notches 9 in one edge thereof, and headed stop pins or screws 10 are located in the strips 13 in position to enter the open notches with their heads back of the plates 12, when the screen 40 is swung into vertical position. The stop pins 10 are so located that they will engage with the plates when the screen has been moved a suitable distance to cause the guide pins 8 to pass up into the slot 6 as shown 45 in Fig. 5, which illustrates the relative positions of the pins 8 and 10 in the plates 5 and 12, when the screen is in proper position in the window. When the pins 10 are 50 located in the open notches 9 accidental movement of the screen in the direction of its length, and hence disengagement of the pins 8 from the slot 6 is prevented until the screen is swung outward. The recesses or 55 notches 9, accordingly, to the extent indicated, act as locking means for the screen.

It will be observed that the insertion and removal of the screen may be easily accomplished, and that when in place the screen 60 will be locked against removal in any direction except by pulling the screen backwardly into the room, so as to tilt it as shown in Fig. 3. It will also be seen that the screen when in place permits the sash to be freely raised and lowered as the sash slides 65 inside of the screen instead of being ar-

rested by engagement with the upper edge of the screen, as is usual with adjustable screens. A further advantage of the construction described is that free access may be had to the space outside of the window by 70 merely tilting the screen to an inclined position, and without removing it from its connection with the window. A still further advantage of this means of mounting an adjustable screen is that the heads of the 75 screws 8, 10, will, by engagement with the plates, prevent accidental inward sliding of the screen sections when the screen is in place.

In the construction illustrated in Figs. 11 80 and 12 the form of plates and screws as shown in Figs. 4 and 5 is applied to a solid or non-adjustable screen, the arrangement of the plates 5 and 12, having the slots 6, 85 openings 7, and openings 9 being the same as in the application of the invention to adjustable screens as heretofore described.

Changes may be made in the several parts described or in the details thereof, without departing from the principles of the invention, provided such changes or variations do not depart from the scope of the following 90 claims.

I claim:—

1. A screen comprising a frame having 95 recesses in its side rails, plates secured to the side rails over said recesses and provided with longitudinal slots having lateral 100 openings, said side rails having recesses below the first mentioned recesses, and plates having open notches over said lower recesses, of headed pins in the window guiding strips located in position to enter the lateral openings in the first-mentioned 105 plates and arranged to pass into the longitudinal slots in said plates, and other pins in said window guiding strips arranged to enter the openings in the last-mentioned plates to prevent longitudinal movements or 110 the outward swinging of the screen. 110

2. An adjustable screen comprising two relatively sliding members, dove-tail tongues and grooves in the upper and lower rails of the frames of said members, the dove-tail tongues extending substantially 115 the entire length of the rail of one of said members, a pawl pivotally mounted to a face of the rail beyond said tongue, and a shoulder formed at the extremity of the groove for cooperation with said pawls. 120

3. A window screen comprising, in combination, two slidably adjustable sections, the upper and lower rails of one of said sections having dove-tail tenons extending 125 nearly to the end of said rails, pawls pivotally mounted in said rails beyond said tenons, and the upper rail having an inwardly extending strip arranged to fit against the outer face of a sash rail, the upper and lower rails of the other screen sec- 130

- tion having grooves to cooperate with said tenons and shoulders at the extremities of said grooves for engagement by said pawls to limit the extension of said sections, and 5 opposite pairs of plates having slots and openings therein located at the outer edges of said sections at suitable distances apart, and headed screws arranged to be secured to opposite sash guiding strips in position for entering the openings and slots in said 10 plates to removably retain the screen sections in position.

In testimony whereof I have hereunto set my hand this 30th day of October A. D. 1923.

HANSON TAMS.
